LOOP-TAKER MECHANISM FOR SEWING MACHINES

Walter Myers, Bridgeport, Conn., assignor to The Singer Manufacturing Company, Elizabeth, N. J., a corporation of New Jersey

Application December 4, 1941, Serial No. 421,528

6 Claims. (Cl. 112—184)

This invention relates to loop-taker mechanisms for sewing machines and more particularly to loop-taker mechanisms of the vertical-axis rotary hook type, i. e., of the type in which the rotary hook rotates about an axis substantially parallel to the path of reciprocation of the sewing machine needle.

The present invention has for its primary object to facilitate replacement of a sewing machine rotary hook, as for example a worn-out or a damaged rotary hook. A further object of the invention is to facilitate assembly of a rotary-hook actuating mechanism in a supporting bracket of the sewing machine. Other and more specific objects of the invention will be apparent from the following description and claims.

The invention consists in the devices, combinations and arrangements of the parts of a rotary hook actuating mechanism as hereinafter described in connection with the accompanying drawing, in which:

Fig. 1 represents an enlarged vertical section, partly in front elevation, of a portion of a sewing machine containing the improved rotary-hook actuating mechanism. Fig. 2 represents a reduced vertical-section, partly in side elevation, of a slightly modified form of the rotary hook mechanism, the rotary hook and its shaft being omitted and the section being taken transversely of Fig. 1. Fig. 3 is a top-plan view of a conventional ball-bearing abutment ring. Fig. 4 is a top-plan view of a substitute sectional abutment-ring.

The present invention is in the nature of an improvement in the vertical-axis rotary hook mechanism of my prior U. S. Patent No. 2,236,830, April 1, 1941. The sewing machine has the usual frame-bed 1 provided with work-supporting slide-plates 2 and 3, and with a throat-plate 4 disposed between said slide-plates.

Depending from the frame-bed 1 is a lug 5 provided with a horizontally apertured bearing-bushing 6. A loop-taker and feed actuating shaft 7 is rotatably journaled in the bearing-bushing 6 to extend horizontally lengthwise of the bed 1. Carried by the rotary shaft 7 is a feed-lift eccentric 8 engaged by a feed-bar 9 provided with a feed-dog 10. The feed-dog 10 operates through feed-slots 11 in the throat-plate 4 and is actuated to cooperate, in the usual manner, with one or more endwise reciprocating and laterally vibratory thread-carrying needles 12 in advancing the work. The feed-dog 10 is opposed by the usual spring-depressed presser-foot 13.

Complemental to the right hand needle 12, in the formation of lock-stitches, is a rotary hook

14 of the vertical-axis type, i. e., of the type in which the hook rotates about an axis substantially parallel to the needle 12. As more fully disclosed in my prior Patent No. 2,236,830, the rotary hook has a cup-shaped body including a bottom wall 15 and a generally cylindrical side wall 16 provided with a needle-thread loop seizing beak 17. Journaled in the side wall of the rotary hook body is a thread-carrier 18 restrained against rotation with the rotary hook. The bottom wall 15 of the rotary hook has a depending hub-flange 19 preferably integral with a vertically disposed rotary-hook shaft 20 provided with a longitudinal bore 21. The bore 21 of the hook-shaft extends through the bottom wall 15 and its hub-flange 19 of the hook-body, and the upper end of said bore terminates in a countersink 22 in the inner face of the hook bottom wall 15. The hook-shaft bore 21 opens into an enlarged counterbore 23 formed in the lower portion of the hook-shaft 20. Disposed in said counterbore 23 is the reduced stem 24 of an eccentric 25 held in engagement with the lower end of the shaft 20 by a screw 26. To this end, the screw 26 is passed downwardly through the bore 21 of the hook-shaft and is threaded into the stem 24 of the eccentric 25, the head 26' of said screw being disposed in the countersink 22 of the hook-body. The eccentric 25 is locked to the hook-shaft 20 for rotation in timed relation therewith by means of a pin 27 extending transversely through the stem 24 of the eccentric and entering suitable notches, as 28, in the lower end of the hook-shaft.

The hook-shaft 20 is rotatably supported by a bracket or hook-saddle 29 which is disposed below the work-support of the machine and, as usual, is in part supported by a reduced portion 30 of the bearing-bushing 6. The hook-saddle 29 is cut away to provide a gear-clearance cavity 31 between vertically spaced walls 31 and 32. The upper wall 31 of the hook-saddle has a vertical annular opening 33 and the lower wall 32 of the hook-saddle is likewise provided with an annular opening 35 which is coaxial with and is in the present case, diametrically of substantially the same size as the opening 33 of the upper wall. The lower portion of the opening 35 of the lower wall 32 is enlarged to provide a threaded counterbore 36.

Detachably secured by a screw 37 upon the hook-shaft 20, intermediate the ends thereof, is the hub 38 of a spiral pinion-gear 39. The hub 38 of the pinion-gear comprises, in effect, a tubular sleeve having the pinion-gear 39 inter-

mediate the ends of the sleeve. The hub-sleeve 38 has diametrically reduced end-extensions 48 and 49, upon each of which is force-fitted the inner race-ring of a ball-bearing 42. The outer race-ring of the upper ball-bearing 42 is slip-fitted into the bracket-opening 33 of the upper bracket-wall 31, and the outer race-ring of the lower ball-bearing 42 is similarly fitted into the opening 35 of the lower bracket-wall 32. The outer race-ring of the lower ball-bearing 42 is circumferentially grooved to receive a conventional split abutment-ring 43 adapted to engage the bracket-shoulder 44 formed by counterboring the lower bracket-wall opening 35. The assembly unit, comprising the pinion-sleeve 38 and the ball-bearings carried thereby is vertically positioned in the bracket 29 by a screw-plug 45 threaded into the counterbore 36 of the bracket-wall 32 to hold the abutment-ring 43 in engagement with the bracket-shoulder 44. The screw-plug 45 may be suitably locked by a screw 46, Fig. 2.

The bracket-cavity 30 is closed by a detachable end-closure plate 47 and access to the pinion-gear securing screw 37 is afforded through an aperture 48 in the front wall of the bracket 29, said aperture 48 being normally closed by a screw 49. The pinion-gear 39 is engaged, in the usual manner, by a spiral-gear 50 having its hub 51 suitably secured upon the actuating shaft 7.

As more fully described in my prior Patent No. 2,236,830, the eccentric 25 engages the fork of a crank-arm 52 carried by the lower end of a vertically disposed rock-shaft 53. The rock-shaft 53 is journaled eccentrically in a bushing 54 adjustably secured in the bracket 29 by a screw 55. At its upper end, the rock-shaft 53 carries escapement-fingers, as 56, adapted to enter apertures, as 57, provided in the thread-carrier 18, thereby to restrain the thread-carrier against rotation with the rotary hook. Detachably secured upon the bottom wall of the supporting bracket 29 is a dished closure-plate 58 which houses the hook-shaft eccentric 25 and the crank-arm 52 actuated thereby, said closure-plate also functioning as an oil-holding reservoir.

The wall 31 of the supporting bracket 29 is counterbored in the upper side thereof to form an annular recess 59 entered by the flange 19 of the rotary hook. Disposed in the recess 59 to overlie the upper ball-bearing 42 is a circular trough 60 having a central clearance aperture 61 for the hook-shaft 20; said trough 60 functioning as an oil-well.

Depending from the rotary-hook flange 19 is a tubular scoop 62 having its open lower end disposed in close proximity to the bottom wall of the oil-well 60. As more fully illustrated and described in my prior U. S. patent application Serial No. 374,421, filed Jan. 15, 1941, the tubular scoop 62 functions during the operation of the machine to pick up oil from the well 60; the oil being supplied to said well through an aperture 63 in the side wall of the oil-well 60. Under centrifugal force and through suitable ducts (not shown) the pick-up oil is conducted to the usual bearing for the thread-carrier 18 in the rotary hook 14.

In order to limit the quantity of oil contained in the oil-well 60, the outer wall of said oil-well is provided with a discharge-port 64, illustrated in Fig. 2 of the drawing. The discharge-port 64 is preferably disposed at substantially the same level as the open lower end of the tubular scoop 62. The discharge-port 64 opens into an

upwardly open pocket 65 formed in the bracket 29 to intersect in part the recess 59, thereby providing an opening in the side wall of the recess 59 above the rim of the oil-well 60. The bottom wall of the pocket 65 is connected by a duct 66 with the gear-clearance cavity 30 in the bracket 29, from which cavity the excess oil drains into the bottom closure-plate 58. To induce discharge of oil from the oil-well 60, a pad 67 of felt or other suitable oil-absorbent material is preferably placed in the oil-well 60 so as to be disposed in the region of the discharge-port 64. The pad 67 is preferably held below the rim of the oil-well 60 by means of a spring 68 confined in the pocket 65 by a pocket-closure disk 69 set into the bracket 29. The flange 18 functions as an oil-sling, and the oil thrown off by the flange 18 is free to drain into the pocket 65 through the opening in the side wall of the recess 59 above the rim of the oil-well 60.

Instead of providing the lower ball-bearing 42 with the conventional abutment ring 42, as illustrated in Figs. 1 and 3, the upper ball-bearing 42 may be provided with an abutment-ring 70 disposed in a circumferential groove in the outer race-ring, as shown in Fig. 2. The abutment-ring 70 is made in sections as illustrated in Fig. 4 and is applied to the upper ball-bearing 42 after the pinion-gear sleeve 38 has been inserted through the opening 35 of the lower bracket-wall. The abutment-ring 70 engages the upper wall 31 and is held thereagainst by the screw-plug 45. This arrangement is a preferred modification in cases wherein it is desirable to positively resist an upward thrust imposed upon the pinion-gear sleeve 38 by the gears 50, 39.

As hereinbefore described, the pinion-gear sleeve 38, together with the ball-bearings 42 and the split abutment-ring 43 assembled therewith are inserted through the counterbore opening 36 in the bracket 29 to seat the outer race-rings of the ball-bearings 42 in the bracket-recesses 33 and 35. The screw-plug 45 is then threaded into the counterbore 36 to force the abutment-ring 43 against the bracket-shoulder 44. The driving gear 50 is then shifted lengthwise of the shaft 7 into proper mesh with the pinion gear 39, whereupon the driving gear 50 is secured to the shaft 7. The rotary hook-shaft 20 is then passed downwardly through the sleeve 38 of the pinion-gear, and the stem 24 of the eccentric is inserted upwardly into the bore of the hook-shaft 20; said shaft and eccentric-stem being secured together by means of the elongated screw 26. The rotary hook may now be conveniently timed with respect to its needle 12, whereupon the sleeve 38 may be detachably secured to the hook-shaft 20 by means of the set-screw 37.

This arrangement not only provides convenient means for assembling and accurately timing the rotary hook, but it has the additional and outstanding advantage of providing for removal and replacement of the rotary hook and its shaft without necessitating removal of the end-closure plate 47 of the bracket 29, and without disturbing the intermeshing relation of the driving and driven gears 50, 39. In order to remove the hook and its shaft 20, it is merely necessary to loosen the set-screw 37 from the hook-shaft and to unthread the screw 26 from the stem 24 of the eccentric 25. After removal of the hook and its shaft, the pinion 39 remains in mesh with its driving gear 50 and the pinion-gear sleeve 38 remains in its proper position in the bracket 29, inasmuch as said sleeve is confined by the bracket

29 against bodily sidewise movement. Consequently, it is a simple matter to insert another hook and hook-shaft into the properly positioned pinion-gear sleeve 38.

While only one rotary hook mechanism is illustrated in the drawing, it is to be understood that the sewing machine contains a similar rotary hook mechanism for cooperation with the left hand needle 12.

Having thus set forth the nature of the invention, what I claim herein is:

1. Rotary-hook mechanism for sewing machines, comprising, a supporting bracket having spaced walls providing therebetween a gear-clearance cavity, ball-bearings disposed in said walls of the bracket, a tubular sleeve rotatably journaled in said ball-bearings, a pinion-gear carried by said sleeve and disposed between said walls, a rotary-hook carrying shaft disposed within and detachably secured for rotation with said sleeve, and means including a driving gear in engagement with said pinion-gear for rotating said shaft.

2. Rotary-hook mechanism for sewing machines, comprising, a supporting bracket having spaced walls provided with coaxially disposed annular openings, ball-bearings seated in the respective openings of said walls, a tubular sleeve having opposite ends thereof rotatably journaled in said ball-bearings, said sleeve being provided between said walls with a pinion-gear smaller diametrically than one of said openings, and a rotary-hook carrying shaft disposed within and detachably secured to said sleeve for rotation therewith.

3. Rotary-hook mechanism for sewing machines, comprising, a supporting bracket having spaced walls each of which is provided with an annular opening, a tubular sleeve having the opposite ends thereof extending into the openings of said walls, a pinion-gear carried by said sleeve between said walls, ball-bearings including inner race-rings mounted upon the opposite ends of said sleeve and complementary outer race-rings seated in the respective openings of said walls, and a rotary-hook carrying shaft disposed within and detachably secured to said sleeve for rotation therewith.

4. Rotary-hook mechanism for sewing machines, comprising, a supporting bracket having spaced walls each of which is provided with an annular opening, a tubular sleeve having the opposite ends thereof disposed in the openings of said walls, a pinion-gear carried by said sleeve between said walls, ball-bearings including inner race-rings mounted upon the opposite ends of said sleeve and complementary outer race-rings

5 seated in the respective openings of said walls, means including an abutment-ring carried by the outer race-ring of one of said ball-bearings and secured against said bracket for holding said sleeve against endwise movement, and a rotary-hook carrying shaft disposed within and detachably secured to said sleeve for rotation therewith.

6. Rotary-hook mechanism for sewing machines, comprising, a supporting bracket having spaced walls provided with coaxially disposed annular openings, a tubular sleeve provided with a pinion-gear disposed between said walls, said sleeve having the opposite ends thereof extending into the openings of said walls, ball-bearings including inner race-rings mounted upon said sleeve at opposite sides of said pinion-gear and complementary outer race-rings seated in the respective openings of said walls, one of said outer race-rings being externally provided with a circumferential groove, a sectional abutment-ring disposed in said circumferential groove, means engaging one of said outer race-rings for clamping said abutment-ring against one of the walls of said bracket, and a rotary-hook carrying shaft disposed within and detachably secured to said sleeve.

7. Rotary-hook mechanism for sewing machines, comprising, a supporting bracket having spaced walls provided with coaxially disposed annular openings, a rotary-hook carrying shaft rotatably journaled in said openings of the bracket, and a pinion-gear detachably secured upon said shaft and disposed between said walls, said pinion-gear having a hub confined by said bracket independently of said shaft against bodily sidewise movement.

WALTER MYERS.
